UNITED STATES PATENT OFFICE.

CHARLES E. ADAMSON, OF HUNTINGTON, INDIANA.

APPLIANCE FOR PRODUCING AND BURNING ALCOHOL GAS.

Application filed July 20, 1921. Serial No. 486,298.

To all whom it may concern:

Be it known that I, CHARLES E. ADAMSON, a citizen of the United States, residing at Huntington, in the county of Huntington and State of Indiana, have invented certain new and useful Improvements in Appliances for Producing and Burning Alcohol Gas, of which the following is a specification.

My invention relates to a method and appliances for producing and burning alcohol gas.

One of the objects of my invention is to convert industrial alcohol into gas and so arrange the parts that the conversion takes place between the supply of alcohol and the consumption of the gas so that conversion takes place while feeding alcohol toward the burner.

Another object of my invention is to employ a method in which the alcohol is subjected to heat while passing through what I term an erratic or tortuous travel line and in progressively expanding the gas on its course along said travel line.

Heretofore, in appliances for converting liquid fuel into gas and providing the appliance with means for burning the gas, the fuel was permitted to flow from the source of supply in a continuous unbroken stream and a continuous coil employed from end to end of the passage to which the fuel was fed, with the result that the heat was conducted along the entire length of the coil and the alcohol consequently forced back into the source of supply, due to the fact that less resistance was offered at the feeding end of the coil than at the discharge end. Consequently, the appliance, usually including a burner, was rendered more or less ineffective.

Another object of my invention is to provide a device for converting alcohol into gas in which the liquid alcohol is fed into a conduit or tube having means therein heated in a progressive manner.

A further object of my invention is to provide a device for converting liquid alcohol into gas on its way from a source of supply to a burner, and in which the conduit or passage to which the alcohol is fed is provided with separated coils which become heated progressively to a higher degree toward the discharge end thereof.

A still further object of my invention is to provide a device of this kind with separated coils so that each will absorb and prac-

tically retain its own heat, thus permitting the coils to become heated to a greater degree progressively toward the discharge of the tube, due to the gradual conversion of liquid alcohol into gas along its course through and around the coils.

A still further object of my invention is the provision of a device of this kind, including a tube having separated coils abutting end to end with alternate coils filled.

With the above objects in view, my invention relates to the novel method of converting liquid alcohol into gas, and to the novel features of construction and the arrangement and combination of parts to be herein-after described and more particularly pointed out in the subjoined claims.

While my invention is adapted for use for various purposes, I have illustrated the same in connection with a portable stove or heating chamber, but it is apparent that the same is especially adapted for use in a sad iron, due to the comparatively small size of the device, which permits its insertion within the body portion of an iron.

In the drawings:—

Fig. 1 is a central vertical section through a heating chamber or, what may be termed a portable stove, equipped with my improved invention.

Fig. 2 is an enlarged horizontal section taken on line 2—2, Fig. 1, parts of the burner tubes and a part of the gas conducting tube being shown in elevation.

Fig. 3 is an enlarged vertical section through the complete device taken on a plane indicated by line 3—3, Fig. 2.

Fig. 4 is a cross section taken on line 4—4, Fig. 3.

Fig. 5 is an enlarged longitudinal section taken through a portion of the converter tube.

Figs. 6 and 7 are cross sections through the converter tube taken on lines 6—6, and 7—7, respectively, of Fig. 5.

The reference numeral 10 designates a portable oven or heating chamber having an opening in its top closed by a lid 11. This heating chamber may be supplied with air in any suitable manner.

12 designates an alcohol supply tank, which is adapted to feed liquid alcohol by gravity to my improved device within the stove or heating chamber. A vertically-disposed pipe 13 is secured to the bottom of said

65

supply tank, and by means of an elbow or other suitable fitting 14, said vertically-disposed pipe is connected with what I term the converter tube 15, to which the liquid alcohol 5 is fed and in which it is converted from liquid fuel into a gas to be discharged from a valve-controlled fitting 16 into which the converter tube is secured. Said fitting 16 has a small discharge opening 17 in communication with the end of the converter tube, the amount of gas passing from the converter tube through said fitting 16 and escaping from the outlet 17 being controlled by a needle valve 18, which may extend out 10 through the wall of the stove or heating chamber so that it can be easily regulated.

19 designates a gas inlet-tube having its inlet end spaced a short distance from the discharge opening 17 of the fitting 16 and 20 having said end preferably flared, as at 20, to allow air to enter said tube with the gas forced out through said discharge opening 17. The opposite end of said air inlet-tube is threaded into a fitting or manifold 21, 25 which has a passage 22 therethrough leading to opposite ends of said fitting or manifold, and into said opposite ends, burner tubes 23 are threaded or otherwise secured, said burner tubes being parallel with and arranged at opposite sides of the gas inlet-tube 19, the free ends 24 thereof being closed by 30 plugs 25 or otherwise, as may be desired. Each burner tube 23 has gas outlets 26 which are directed upwardly and inwardly against 35 the converter tube 15, said converter tube being positioned directly above the gas inlet-tube 19. Said converter tube is also supported by the fitting or manifold 21 and may be fastened thereto by a clip 27. In this 40 manner the gas inlet-tube 19 and burner tubes 23 are carried by the converter tube and the discharge opening 17 of the fitting 16 to which the converter tube is secured or, as it may be more broadly considered the 45 outlet of the converter tube, is maintained at all times in proper relation to the flared inlet end of the gas inlet-tube.

In its broader sense, the vertically-disposed tube 13 may be considered as forming 50 part of the converter tube, it being optional as to whether or not the vertically-disposed portion 13 of the converter tube is secured to the horizontal portion 15 thereof by means of the fitting 14, or whether a single tube is 55 employed bent to form the vertically-disposed and the horizontally-disposed portions.

Within the converter tube, in the particular instance illustrated, within the horizontal portion of the converter tube, a plurality of retarder elements in the form of closely wound coils 28, 29, 30, 31 and 32 are fitted, said coils being preferably of a diameter to snugly fit within the tube 15 and 60 arranged to abut end to end or be slightly

separated one from the other, the coils being alternately filled, as by means of lengths of wire 33, preferably of a diameter to snugly fit within the coils, the preferred arrangement being that in which the first coil of the 70 series is filled, and alternately open-center and filled coils are arranged throughout the converter tube. If desired the coils may be extended up through the vertical portion 13 of the tube. These coils serve to create pressure at the gas discharge opening 17 and also to prevent pressure rearwardly, or into the alcohol tank, which would prevent proper feeding of the gas to the burners, and therefore the greater the number of coils employed the more effective will be the results. 75

Resting on the bottom of the stove or heating chamber 10 is a pan 34 on which the fittings 16 and 21 rest, a piece of asbestos or other non-combustible material 35 being inserted between the fitting 16 and the pan and extending beneath the adjacent ends of the gas inlet-tube 19 and burner tubes 23. 85

The alcohol fed by gravity into the converter tube passes through the first coil 28 under considerable friction, and as this coil and the coils 30 and 31 are filled with lengths of wire 33, very small spiral passages 36 are formed between said wire 33 and the convolutions of the coils, and similar spiral passages 37 are formed between all the coils and the surrounding tube 15. The small passages 36 and 37 of the first coil 28 are therefore completely filled with alcohol, the alcohol having a circular or whirling action 90 while passing through and around the first coil 28 and escaping from the farther end thereof, where it enters the second coil. Alcohol passing through and around or along the first coil 28 is subjected only to such heat 95 as is carried along the tube 15 surrounding it, due to the fact that the flames from the burner tubes do not come in direct contact with that portion of the tube 15 surrounding said coil. For this reason the gas created 100 within the tube will exert its pressure mainly against the first filled coil 28 and be thereby prevented from acting against a solid body of liquid alcohol to prevent feeding of the 105 same into the converter tube. 110

The alcohol entering the second coil 29, which is unfilled and therefore has a central passage therethrough, passes through and around it, it being allowed to expand within the central passage of said second coil, due 115 to the fact that the flames of the burner tubes play against that portion of the tube 15 surrounding said second coil; the heat to which said last-mentioned portion of the tube is subjected having a tendency to create 120 gas within and around said second coil.

When the gas and remaining non-converted liquid leaves the second coil and comes in contact with the third coil, which is filled, 125 the gas thus far created with any non-con- 130

verted alcohol will flow through and around said third coil passing circularly or spirally through the small spiral passages 36 and 37, and as this coil is heated to a greater degree than the second coil, any unconverted liquid will be converted into gas along this region.

As the gas leaves the third coil, which is filled, the resistance to travel backward is considerably greater than that offered against its forward travel, and the gas then enters the fourth coil, which is unfilled and therefore has a central passage therethrough, where it is further expanded and heated to a greater degree. The gas, highly heated, then leaves the fourth coil and passes through the small spiral passages 36, 37 of the fifth coil, where it is still further heated due to its being divided and caused to pass through said small passages. The heat is therefore progressively applied to the coils from the inlet end of the converter tube toward the outlet end thereof and consequently the highly heated gas enters the fitting 16, or valve chamber as it may be termed, and has a free escape therefrom when opening the valve 18. It may here be noted that the central passages through the unfilled coils serve as expansion spaces.

The separation of the coils is made for the purpose of having each coil retain its own heat, and as the coils are heated to a higher degree progressively as they are farther from the alcohol supply, a gas of high heating units is secured, which will be directed into the inlet-tube 19 of the burner and from the latter be directed into the burner tubes 23, where it is ignited at the openings 26, the flames playing against the converter tube 15 while heating the interior of the stove or chamber and particularly the lid 11 thereof.

The gas passing into the burner tubes 23 will be under considerable pressure, and this pressure may be increased by increasing the length of the converter tube and the number of coils therein, or by placing the alcohol tank at a higher elevation with the same number of coils within the converter tube. By causing the alcohol or gas to pass alternately through filled and unfilled coils, they are given an erratic or tortuous course of travel. For example, in passing through the first coil 28, a circular or spiral motion is given the alcohol, and when leaving said coil, part of the alcohol is directed at a right angle, or substantially so, in entering the second coil, which is unfilled, and this change in course of alcohol, or gas, depending on the stage of conversion, takes place

each time it leaves one coil and enters another.

When starting the device it will be necessary to heat the converter tube before gas can be produced, and when said tube is not subjected to heat, the liquid from the gas tank will flow through said tube when the valve 18 is opened. Therefore it is simply necessary to open the valve 18 and allow a small quantity of the liquid fuel to saturate the piece of asbestos 35 and also allow it to flow onto the pan 34. This alcohol may be ignited by removing the lid, and when lighted will heat the converter tube sufficiently to generate gas within the same. When the desired quantity of alcohol is delivered to the piece of asbestos 35 and the pan 34, the valve will be closed so that conversion of alcohol into gas will take place within the tube and so that gas will not escape until sufficient pressure has been generated to carry it through the gas inlet-tube 19 to the burner tubes 23, which gas will then become automatically ignited from the burning alcohol within the pan.

Having thus described my invention, what I claim is:—

1. A device for converting alcohol into gas, comprising a tube having an inlet at one end and a controlled outlet at its other end, and coils fitting within said tube and arranged successively from the inlet toward the outlet thereof, alternate coils being provided with filler elements.

2. A device for converting alcohol into gas, comprising a converter tube having an inlet at one end and a controlled outlet at its other end, a plurality of closely wound coils fitting within said tube with alternate coils provided with filler elements in contact with the convolutions of the coils at all points circumferentially.

3. The combination with a liquid fuel tank, a tube connected to said tank and having its inlet at said tank, a plurality of closely wound coils fitting snugly within said tube and arranged end to end, cylindrical filler members fitting snugly within alternate coils, a valve connected to said tube to control the flow of liquid fuel and gas therefrom, a gas inlet-tube spaced from said valve and adapted to receive the gas therefrom, a fitting connected to said gas inlet-tube and supporting said first-mentioned tube, and burner tubes connected to said fitting and arranged to direct the flames thereof against said first-mentioned tube.

In testimony whereof I affix my signature.

CHARLES E. ADAMSON.
